UNITED STATES PATENT OFFICE.

JULIUS C. STROM, OF SILVERTON, OREGON.

SLIDING-DOOR HANGER.

1,325,123.

Specification of Letters Patent. Patented Dec. 16, 1919.

Application filed July 22, 1918. Serial No. 246,064.

To all whom it may concern:

Be it known that I, JULIUS C. STROM, a citizen of the United States, residing at Silverton, in the county of Marion, State of Oregon, have invented certain new and useful Improvements in Sliding-Door Hangers; and I do hereby declare the following to be a full, clear, and exact description of the invention, such as will enable others skilled 5 in the art to which it appertains to make and use the same.

The invention relates to a sliding door guide attachment and more particularly to the class of keeper devices for sliding door 15 hangers, used especially upon doors of the edgewise movable type, yet the device may be employed on railway car doors or other like door structures.

The primary object of the invention is, 20 the provision of a device of this character, wherein the sliding door hanger carries a guide roller engaged by a keeper so as to prevent the track roller of the hanger from jumping or moving off of the track when the 25 door is being moved, and at the same time permit the door to be easily moved and free from wobbling action or vibrations incident to the travel of the door.

Another object of the invention is, the 30 provision of a device of this character, wherein the keeper is supported under tension so as to maintain it in proper relation to the guide rollers or hangers for the sliding door the keeper and the mounting there- 35 of being novel in form and will prevent looseness or vibratory movements of the door at its bottom or when being opened or closed.

A further object of the invention is, the 40 provision of a device of this character, which is simple in construction, reliable and efficient in its operation, and inexpensive to manufacture and install.

With these and other objects in view, the 45 invention consists in the features of construction, combination and arrangement of parts as will be hereinafter fully described, illustrated in the accompanying drawing and pointed out in the claims hereunto ap- 50 pended.

In the accompanying drawing:

Figure 1, is a side elevation of a door showing the device supported in accordance with the invention, as applied to a barn.

Fig. 2 is a fragmentary vertical trans-

verse sectional view taken through one of the hangers of the door.

Fig. 3, is a sectional view on the line 3—3 of Fig. 1.

Fig. 4, is an edge view of the door with 60 the hanger and supported by the track.

Fig. 5, is a plan view of the keeper rod.

Similar reference characters indicate corresponding parts throughout the several views in the drawing.

Referring to the drawing in detail, A, designates generally the door which is of the edgewise movable type having suitable bracket 10 attached to its upper end, each bracket being in the form of a hook shaped 70 hanger having journaled therein a track roller 11, the brackets 10 being vertically disposed and in spaced relation to each other and the track rollers 11 are engaged with and adapted to travel upon a track secured 75 to the outside of a barn or other structure. The track comprises a plurality of plate-like sections 12 having notched meeting ends 13 which are arranged in over lapped relation to each other to form a smooth joint between the sections 12, which are disposed in vertical edgewise relation and are secured in any suitable manner to brackets 14 spacing the track outwardly from the outside of the barn or other structure, the brackets 80 14 being preferably of U-shape having feet 15 secured to the barn or other structure above the doorway adapted to be opened and closed by the door A on movement thereof.

Mounted near the ends of the track are uprights or standards 16 formed with the lower forks 17 which straddle the track and are secured thereto in any suitable manner for fixing the standards in vertical position.

Supported by the standards 16 above the track for vertical movement is a keeper comprising a rod 18 disposed parallel with the track and formed with terminal eyes 19 which engage upon the standard 16 and 100 loosely embrace the same.

In each hanger 10 above the track roller 11 is journaled a guide roller 20 against which plays the keeper rod 18 and surrounding the standard 16 are coiled expansion 105 springs 21 which work against the terminal eyes 19 of said rod 18 and also against adjusting nuts 22 carried on the upper ends of the standards 16 so that the tension of the springs 21 can be varied on adjusting 110

the nuts 22 upon the said standards 16 and thereby increasing or decreasing the pressure of the keeper rod 18 upon the guide rollers 20 in the hangers 10 movably supporting the door.

It will be apparent that by the use of the keeper rod 18 which is vertically movable and under tension by the springs 21 to play upon the guide rollers 20, in the hangers 10, on the door A, the track rollers 11 will be prevented from jumping off or running from the track constituted by the sections 12, yet the said door is freely movable edgewise for the opening and closing 15 of the doorway in the barn, or other structure. The device will serve to prevent looseness or vibratory movement of the door and sustain the track rollers 11 in proper working relation to the track and thereby 20 successfully support the door for movement in suspended relation to the track by the hangers.

It is of course to be understood that changes, variations and modification will be 25 made in the invention such as come properly within the scope of the appended claims, without departing from the spirit of the invention or sacrificing any of its advantages. The device in the embodiment there- 30 of hereinbefore set forth generally improves the mounting of the hangers of a sliding door and overcomes the source of serious inconvenience ordinarily incident to the working 35 of the door and in the movements thereof.

What is claimed is:

1. The combination with a track, and a door; of a pair of hangers carried by the door, rollers carried by the hangers and

traveling upon the track, additional rollers 40 carried by the hangers above the track, a keeper parallel with the track and overlying said additional rollers, and spring supports beyond both limits of movement of the door arranged to urge said keeper, and therewith 45 the hangers with their rollers toward the track.

2. The combination with a track and a door of hangers connected to the door, rollers carried by the hangers engaged upon the 50 track, guide rollers carried by the hangers free from the track, a keeper parallel with the track engaged upon the guide rollers and having terminal eyes, uprights with which the keeper is engaged through the 55 medium of its eyes and springs carried by the uprights upon the keeper and having means for tensioning them in the direction of the track to correspondingly urge the keeper.

3. The combination with a track and a movable door, of hangers carried by the door, track rollers journaled in the hangers and movable over the track, guide rollers journaled in the hangers above the track 65 rollers, a keeper supported above the track and engaged by the guide rollers, vertical uprights with which said keeper is slidably engaged, and tension means on the uprights and working against the keeper to vertically 70 tension the same.

In testimony whereof I affix my signature in the presence of two witnesses.

JULIUS C. STROM.
